UNITED STATES PATENT OFFICE.

HARALD NIELSEN, OF MIDDLESEX, AND FREDERICK DEACON MARSHALL, OF WEST MINSTER, LONDON, ENGLAND.

HEAT-EXCHANGE APPARATUS.

1,378,715.

Specification of Letters Patent. Patented May 17, 1921.

Application filed September 11, 1920. Serial No. 409,663.

To all whom it may concern:

Be it known that we, HARALD NIELSEN, a subject of the King of Denmark, and FREDERICK DEACON MARSHALL, subject of the 5 King of Great Britain, residing at, respectively, 13 Firs avenue, Muswell Hill, Middlesex, England, and 19 Queen Anne's Chambers, Westminster, London, England, have invented new and useful Improvements in Heat-Exchange Apparatus, of 10 which the following is a specification.

Our invention relates to heat exchange apparatus or superheaters for use in connection with producer-gas plant, or plant for 15 the re-heating of coke oven gas.

For the purpose of our invention we employ an apparatus for effecting an exchange of heat which comprises a closed casing or container within which is arranged a series 20 of flat, oblong closed boxes connected together by short pipes so as to provide a continuous passage for the gas, such as a mixture of steam and air, to be heated, the boxes or heating units being furnished with internal baffle plates to increase the path 25 through which the said gas or mixture is made to travel, and also so disposed relatively to one another as to provide a zig-zag passage. The space between the said 30 boxes or heating units and the inner surface of the casing through which the heating gas or mixture of gases flows is made of such dimensions that the velocity of flow of the latter is relatively slow, thereby facilitating the deposit of dust by gravity 35 upon the upper surfaces of the boxes, the under or more efficient heating surface of the said boxes being left clean for the transmission of heat to the gas passing through 40 said boxes in the most efficient manner.

In connection with an apparatus of the above construction we provide the casing or container with cleaning doors and scrapers, the latter of which may be operated either 45 by hand or mechanically so as to enable the removal of the accumulated dust to be effected during the actual working of the apparatus, without interfering with the continuous operation of the apparatus.

50 It will also be understood that it is possible to provide a large heating surface in a relatively small container or, in other words, to reduce the loss by radiation to the outside atmosphere to a minimum owing to the

restricted surface presented to the outside 55 air.

The container is extended downward so as to form a receiver or hopper for the dust collected, which can then be removed continuously or intermittently by any well known contrivance. Furthermore, a portion of this collector can be provided with an inlet opening for the heating gas from the producer or other source and be arranged with internal division plates and the lower 60 portion of the casing filled with water so as to form a water seal, to enable the part of the receptacle containing the heating boxes or units to be cut off from the said producer or other source if desired. 70

The troublesome expansion due to the high temperature is effectually compensated for by the arrangement of the heating boxes in the manner described above without the employment of special expansion pieces 75 such as are found necessary with heat inter-changers of the tubular type.

The heating boxes are preferably of the same width as the casing, but have their ends spaced a distance from the front and rear walls of the casing, and adjacent to each of said boxes a damper is arranged, which dampers are located adjacent to opposite ends of alternate boxes so that when these dampers are closed, a tortuous or zig 80 85 zag passage is provided around all of the boxes. By opening any one of these dampers, a short cut is provided past the adjacent box, thus eliminating its heating agency when desired. 90

In heat interchange apparatus as now generally constructed the gases leaving the apparatus still containing a large amount of sensible heat are conducted away to scrubbing apparatus by means of an uninsulated pipe, or, if a number of interchangers are employed, by means of a common main, the object of which is to cool the gases. By adopting this method a certain amount of heat is lost. Furthermore, the pipe or main 95 100 conducting the steam and air or other blast to the heat-interchanger or interchangers is generally heavily insulated in order to prevent cooling and consequent condensation of the steam in the mixture.

Now, according to our invention we place the steam and air or other blast pipes or main inside the partly cooled gas main by

which two results are obtained, namely, the hot gas is further cooled and the steam and air or other blast is pre-heated to any desirable extent within the limits of the heat 5 available and the condensation of the steam is far more efficiently prevented than by simply lagging or insulating the blast-pipe or main, the hot gases surrounding the steam and air or other blast acting as a 10 most effective insulator.

To enable the invention to be fully understood we will describe it by reference to the accompanying drawing in which:—

Figure 1 is a sectional elevation of a heat- 15 exchange apparatus or super-heater for producer-gas or coke oven-gas constructed according to the invention, and

Fig. 2 is a sectional plan view thereof.

a indicates the closed casing or container, 20 *b* the series of flat closed boxes, which are here shown of an oblong or rectangular shape, *c* the short pipes which connect the said closed boxes together so as to form a continuous zig-zag passage for the gas or 25 mixture to be heated, and *d* the internal baffle plates provided in the closed boxes or heating units *b* to cause the said gas or mixture to follow a tortuous path through each box. *e* is the inlet pipe by which the gas to 30 be heated enters the topmost box or unit *b* and *f* is the outlet pipe by which the said gas leaves the apparatus after having passed through the extended tortuous and zig-zag path indicated by the arrows. *g* indicates 35 the inlet to the casing *a* for the heating gas or mixture and *h* the outlet therefrom, the said gas or mixture flowing through the casing in a direction opposite to that of the gas to be heated, as shown by the arrows, 40 and in the zig-zag space or path provided between the ends of the units *b* and the inside of the casing. The cross sectional area of this space is much greater than that of the inlet pipe so that the gas entering the 45 casing will expand and flow more slowly through the casing than through the pipe *g* and thus afford time to transmit its heat to the gas within the boxes *b*. As shown in Fig. 2, the boxes *b* are of substantially the 50 same width laterally as the casing, but are spaced from the front and rear walls of the casing, and dampers *i* are located in these spaces at opposite ends of alternate boxes as shown in Fig. 1. When these dampers are 55 closed, as therein shown, the heating gas will be forced to take a zigzag path around all of the boxes *b*. The opening of any one of these dampers will provide a short cut for the heating gas past the adjacent box 60 and prevent its receiving as much heat from the heating gases as it would receive were the damper to remain in closed position. These dampers may therefore be used to regulate the temperature of the gas to be heated. 65 *j* shows the scrapers which are provided

in connection with the units *b* for the purpose of clearing deposited dust from the upper surfaces of the said units. These scrapers, in the arrangements illustrated, are designed to be operated by the handles *k* which 70 extend through doors *l* provided in the casing.

The lower end of the closed casing *a* is extended downward to constitute the hopper or collector *m* into which the deposited dust 75 gravitates and from which it can be removed in any convenient way. The inlet *g* for the heating gas opens into this hopper and adjacent thereto there is provided the internal divisional plate or deflector *n* and the 80 lower portion of the casing may be filled with water, as indicated by the dotted line *r* up to a point above the lower end of the deflector *n* to form a water seal, so that the casing may be cut off from the producer or 85 other source of heating gas, if desired, without permitting the escape or back flow of gas to the pipe *g*.

The hot gases leaving the casing by the pipe *h* enter the main *o* and through this 90 main there extends the main *p* through which flows the gas to be heated before passing by the pipe *e* to the exchange apparatus. By this means, as above described, the said 95 gas is pre-heated and condensation is effectively prevented.

Claims.

1. In a heat exchange apparatus, a closed casing having inlet and outlet openings for one of the heat exchanging mediums, a series 100 of closed boxes located within the casing and connected together to form a continuous zigzag passage, inlet and outlet pipes for the other heat exchanging medium connected with said boxes, said boxes being of substantially the same width as the casing, and providing spaces between their opposite ends and the adjacent wall of the casing, and dampers located in said spaces adjacent to opposite ends of alternate boxes. 105

2. In a heat exchange apparatus, a closed casing having inlet and outlet openings for one of the heat exchanging mediums, a series 110 of closed boxes located within the casing and connected together to form a continuous zigzag passage, inlet and outlet pipes for the other heat exchanging medium connected with said boxes, said boxes being of substantially the same width as the casing, and providing spaces between their opposite ends and the adjacent wall of the casing, and dampers located in said spaces adjacent to opposite ends of alternate boxes, the inlet 115 pipe for the first mentioned medium being located adjacent to the lower end of the casing, and a downwardly extending deflector within the casing adapted to extend below the surface of a body of water in the lower end of the casing to form a water seal. 120

3. In a heat exchange apparatus, a closed 125

casing having inlet and outlet openings for one of the heat exchanging mediums, a series of closed boxes located within the casing and connected together to form a continuous zigzag passage, inlet and outlet pipes for the other heat exchanging medium connected with said boxes, said boxes being of substantially the same width as the casing, and providing spaces between their opposite ends and the adjacent wall of the

casing, and dampers located in said spaces adjacent to opposite ends of alternate boxes, a supply pipe communicating with the inlet to said boxes, and a delivery pipe connected to the outlet of the casing and having a portion surrounding a portion of said supply pipe. 15
